THREAD CUTTER FOR TYING MACHINES

Earl Cummins, Kalamazoo, Mich.

Application June 8, 1944, Serial No. 539,392

6 Claims. (Cl. 164—58)

This invention relates to improvements in thread cutter for tying machines.

The main objects of this invention are:

First, to provide a thread cutter for link tying machines in which the blade can be quickly removed and replaced and at the same time one which is effectively and securely supported.

Second, to provide a thread cutter which permits the use of fragments of safety razor blades or the like as blades.

Third to provide a cutter for link tying machines which is well adapted for use in machines now having considerable use.

Objects pertaining to details and economies of the invention will definitely appear from the description to follow. The invention is defined in the claims.

A structure which embodies the features of my invention is clearly illustrated in the accompanying drawing, in which:

Fig. 1 is a fragmentary view of a link tying machine shown diagrammatically and conventionally having my improved cutter associated therewith, only such portions of the machine being illustrated as would be desirable to illustrate a practical application or adaptation of my invention.

Fig. 2 is a fragmentary plan view illustrating the cutter partially advanced to the work and as it is about to sever the tying thread or strand.

Fig. 3 is a perspective view of my improved cutter removed from the machine, the blade clamp being shown in blade releasing position by dotted lines.

Fig. 4 is a fragmentary view mainly in section on line 4—4 of Fig. 2.

Fig. 5 is a perspective view of one of the blades.

In the operation of link tying machines used in the manufacture of link sausages, weiners, and the like, one of the problems is to keep the tying strand or thread cutter in suitable condition. While the operator is expected to keep the blade or cutter to an edge approaching razor sharpness, the tendency is to neglect this, with the result that the edge is dulled and fails to cut the thread, the machine becomes clogged, and the material being packaged is discharged over and into the machine with a general fouling of the apparatus and requiring a shut-down to clean the machine and restore it to operating condition. Further, in such machines as are now generally in use, considerable time is required to remove and replace a blade, and this is one reason why the operator of the machine neglects the blades or

fails to give the attention necessary for the successful operation of the machine.

In the embodiment of my invention illustrated in the accompanying drawing, 1, 1 represent sausage links or weiners, 2 the tying strand or thread which is led from a suitable spool, not illustrated, through suitable guide and tensioning members to the rotary tying head 3. The machine, designated generally by the numeral 14, is 10 designed to feed or advance the stuffed casings through the winding or tying head with a step by step movement. As the details of this mechanism form no part of my present invention I have not illustrated the same herein. The cutter arm 4 is timed to be actuated in proper synchronism with the feeding of the stuffed casings and the operation of the winding head. Again, I have not illustrated the mechanism for securing this timed operation as that forms no part of my invention.

The knife arm is provided with a bracket 5 carrying a suitable stud provided with a clamping nut 6 for securing my improved blade holder 7 to the knife arm. The holder 7 is provided with a laterally opening notch 8 to receive the threaded stud 9 so that the nut 6 may be clamped on to the holder for releasably securing it. The holder is further provided with holes 10 on either side of the notch 8 which engage studs 11 on the bracket 5, thereby securely retaining the blade holder on the arm while permitting its ready removal as occasion may require. The holder is provided with a pair of upwardly projecting laterally spaced studs 12 adapted to engage shoulders 13 formed on the blade 15 by forming opposed notches therein at 16. These notches result in a shank or tang 17 disposed between the studs 12 and rearwardly engaging one of the studs 12. This supports the blade against rearward and pivotal tilting movement with its cutting edge 18 projecting forwardly beyond the holder and preferably in an inclined relation to the tying thread or strand 2 so as to engage the same with a draw cut.

The blades 15 may desirably be formed from razor blades such for example as Gillette blades, but in the accompanying drawing I have not attempted to illustrate the relative thickness of the blades to other parts or the exact bevel of the cutting edge.

The blade is retained by means of the clamp 19 which is provided with a clamping arm 20 extending between the studs 12 and overlapping the blade. The clamp is pivotally and clampingly supported by means of the coiled spring 21 which

is arranged on the pin 22, the pin being arranged through a hole 23. The inner end of the spring engages the under side of the blade holder while its outer end is in thrust engagement with the head of the screw 24, see Fig. 4. The clamp 19 may be lifted from between the studs and swung to position shown by dotted lines in Fig. 3, which releases the blade, and to renew or replace the blade it is only necessary to lay it upon the holder with its tang or shank between the studs and swing the clamp to engaging position. The clamp is supported against pivotal movement when in engaged position by the studs 12 at each side of the finger portion 20.

With this arrangement I not only provide a blade which has a very effective cutting edge, but the blades can be replaced or renewed very quickly and they are very economical. The blades commonly used with this type of machine require frequent grinding and the grinding should be done by a skilled workman. As stated, the blades are often neglected and become dull so that the winding strand or thread is not severed. The result is that the machine becomes clogged and there is usually a considerable loss of time and material in restoring the machine to operation.

I have not attempted to illustrate various modifications and adaptations which I contemplate as I have illustrated my invention in a highly practical embodiment. It is believed that those skilled in the art will be able to adapt my invention as may be desired, not only for the specific use in link tying machines but for other uses where highly effective thread cutters are desired.

Having thus described my invention, what I claim as new and desire to secure by Letters Patent, is:

1. In a cutter of the class described, the combination of a blade holder comprising a plate-like body member having laterally spaced studs thereon, a flat blade having an inclined cutting edge superimposed on said body, said blade having notches extending from opposite edges thereof receiving said studs and providing a shank extending laterally behind one of the studs and in thrust engagement therewith to sustain tilting thrust on said blade, a plate-like clamping member provided with an inclined finger extending between said studs in overlapping clamping relation to said blade, said clamping member having a pin thereon disposed through said body member, and a coiled spring arranged on said pin with its inner end in engagement with the under side of the body member, said pin being provided with a removable thrust member for the outer end of said spring.

2. In a cutter of the class described, the combination of a blade holder comprising a plate-like body member having laterally spaced studs thereon, a flat blade having an inclined cutting edge superimposed on said body, said blade having notches extending from opposite edges thereof receiving said studs and providing a shank extending laterally behind one of the studs and in thrust engagement therewith to sustain tilting thrust on said blade, a plate-like clamping member provided with an inclined finger extending between said studs in overlapping clamping relation to said blade, said clamping member having

a pin thereon disposed through said body member, and a coiled spring arranged on said pin to apply clamping stress to said clamping member.

3. In a cutter of the class described, the combination of a blade holder member having laterally spaced studs thereon, a flat blade superimposed on said holder member with its cutting edge projecting forwardly beyond the holder member, said blade having notch-like recesses extending from opposite edges thereof receiving said studs and providing a shank extending laterally behind one of the studs and in thrust engagement therewith, a blade clamping member provided with a finger extending between said studs in overlapping relation to said blade, said blade clamping member having a pin thereon disposed through said holder member, and a coiled spring arranged on said pin, said pin being provided with a thrust member for the outer end of said spring.

4. The combination in a cutter of a blade holder member having laterally spaced studs thereon, a flat blade superimposed on said holder body member with its cutting edge projecting forwardly thereof, said blade having thrust shoulders in supporting engagement with said studs, and a shank extending between the studs and in rearward engagement with one of them, a blade clamping member provided with a finger extending between the studs in overlapping relation to said blade, said clamping member having a pin thereon disposed through said holder body member, and a spring associated with said pin for applying blade clamping stress to said clamping member, said pin being in longitudinal and pivotal engagement with said holder body member.

5. In a cutter of the class described, the combination of a flat plate-like holder having laterally spaced studs on the face thereof, a flat blade superimposed on said holder member with its cutting edge projecting forwardly beyond the forward edge of the holder member, said blade having notch-like recesses opening to the front and rear edges of the holder member and spaced to receive said front and rear studs with the edges of the notches in thrust sustaining engagement with the studs, and a blade clamping member pivotally mounted on and resiliently biased toward the holder member and provided with a finger extending between and laterally supported by said studs in overlapping relation to the blade and urging it against said holder.

6. In a cutter of the class described, the combination of a blade holder member having laterally spaced upwardly projecting studs thereon, a flat blade superimposed on said holder member with its cutting edge projecting forwardly beyond the forward edge of the holder member, said blade having oppositely disposed notch-like recesses in its front and rear edges providing a shank disposed and supportingly fitting between said studs and shoulders in thrust engagement with said studs, and a blade clamping member provided with a finger extending between and laterally supported by said studs in overlapping relation to said blade, said blade holder being resiliently biased to clamp the blade upon the holder.

EARL CUMMINS.
